UNITED STATES PATENT OFFICE

HENRY C. DAUPHINAIS, OF JAMESTOWN, NORTH DAKOTA

UNDERWEAR SUPPORTING DEVICE

Application filed January 17, 1930, Serial No. 421,447. Renewed March 14, 1932.

This invention relates to underwear supporting devices.

It is found in using long underwear, more especially of the knit type, that the underwear drawers will stretch between the crotch and waistline thereof, permitting the knee portions of the drawers to bag and hang down. The underwear will then tend to bind about the crotch of the wearer and is also liable to rip and tear thereabouts, particularly when the wearer sits down.

It is the object of the present invention to provide novel and improved devices to support the leg portions of underwear drawers, and to prevent undue stretching of the drawers between the crotch and the waistline, thereby eliminating the binding of the underwear about the crotch and also eliminating the possibility of the ripping or tearing of the underwear about the crotch.

To these ends, the invention consists in the novel parts and novel combinations of parts, hereinafter defined in the claims and described in the following specification, made in connection with the accompanying drawing, wherein like reference characters refer to the same or similar parts throughout the various views, and, in which,

Fig. 1 is a view in front elevation of a pair of underwear drawers equipped with a preferred embodiment of the present invention;

Fig. 2 is a vertical section taken on the line 2-2 of Fig. 1, and illustrating the straps of the invention applied to a belt supporting the trousers of a wearer;

Fig. 3 is a view similar to Fig. 2, but it illustrates one of the straps of the invention applied to the lower portion of a pair of suspenders supporting the trousers of a wearer;

Fig. 4 is a view similar to Fig. 1, but illustrating a slightly different embodiment of the invention;

Fig. 5 is a vertical section taken through a pair of underwear drawers and a pair of trousers, and illustrating straps of the same type as those shown in Fig. 4, the said straps being supported from the trousers of the wearer;

Fig. 6 is a view in front elevation of a union

suit equipped with another embodiment of the invention, and

Fig. 7 is a view in front elevation of a portion of one leg of a pair of underwear drawers equipped with yet another embodiment of the invention.

Referring first to the embodiment of the invention illustrated in Figs. 1, 2 and 3, a pair of long underwear drawers composed of knit or other material of the usual type are designated by the numeral 8. In accordance with the present invention, I provide a pair of strong straps 9 composed of less stretchable fabric than the material from which the drawers are constructed. These straps are preferably attached at their lower ends to the front leg portions of the drawers adjacent and preferably slightly below the crotch portion of the drawers, by some suitable means as by means of the stitching 10. The straps 9 extend upwardly to above the waist portion of the drawers and the extreme upper ends of the straps are doubled over on the upwardly extending portions thereof and are stitched by stitching 11 to form a plurality of spaced loops 12 at the upper ends of the straps. When the drawers 8 having the straps 9 secured thereto, are used in connection with a pair of trousers 13 supported by means of a belt 14 extending around the waist of the wearer, as shown in Fig. 2, the upper ends of the straps 9 will be carried over the upper edge of the trousers and the belt 14 will be run through one of the loops 12 in each of the straps 9, so that the straps will depend from and be supported by the belt. As there are a number of loops 12 provided in each of the straps 9, it will be seen that the active lengths of the straps may be adjusted for the requirements of different people by running the belt 14 through different loops 12. In Fig. 3, trousers 15 are illustrated as being supported by suspenders 16, the suspenders being engaged with buttons 17 carried on the inner side of the waistline portion of the trousers. When the trousers are supported by suspenders in this manner, the lower portions of the suspenders may be run through certain of the loops 12 of the straps before at-

attachment of the suspenders to the buttons 17. The suspenders will then act as supporters for the straps. As the straps are composed of material less stretchable than the material forming the drawers, whether a belt or suspenders are used for supporting the upper ends of the straps 9, it will be seen that the straps will act to support the leg portions of the drawers from the clothing of the wearer worn about the waistline, and the straps will relieve the strain on the drawers between the crotch portion thereof and the waist portion thereof, to prevent this portion of the garment from stretching to its extreme limit. There will thus be no danger that the garment will tear or break about the crotch portion thereof. As the straps will support the leg portions of the drawers, the strain on the leg portions of the garment about and below the crotch will be lightened or entirely eliminated to prevent the drawers from binding about the crotch and also to prevent the bagging of the leg portions of the garment at the knees of the wearer.

In Fig. 4, a slightly different embodiment of the invention is illustrated, wherein a pair of drawers are designated by the numeral 18 and detachable straps formed of less stretchable material than the material forming the drawers are designated by the numeral 19. The front of each leg portion of the drawers 18 may be provided with buttons 20 adjacent and preferably a short distance below the crotch, and the straps 19 will preferably be provided with button holes 21 at their lower ends for releasable engagement with the buttons 20. The waist portion of the drawers 8 may also be provided with buttons 22 and the upper ends of the straps 19 may be provided with a series of spaced button holes 23 for adjustable engagement of the upper ends of the straps with the buttons 22. The straps 19 will be supported from the waistline of the drawers and all advantages above enumerated in connection with the use of the straps 9 will be attained.

In Fig. 5, a sectional view of a slightly different embodiment of the invention is shown. The pair of drawers as shown in Fig. 5, are designated by the numeral 24, and a pair of trousers worn over the drawers are designated by the numeral 25. Straps 26, similar to the straps 19 illustrated in Fig. 4, are provided, but the button holes of these straps are illustrated as being connected with suspender buttons 27 sewed to the waist band portion of the trousers 25. In this form of the invention, the straps will be supported and depend from the waist portion of the trousers 25, instead of from the waist portion of the drawers, as illustrated in Fig. 4.

Another different embodiment of the invention is illustrated in Fig. 6. In this view of the drawing, a union suit formed of knit

or other material is designated by the numeral 28 and straps of less stretchable material than the material forming the drawers are designated by the numeral 29. The straps 29 are sewed at their lower ends to the front leg portions of the garment adjacent and preferably slightly below the crotch and they are also sewed to the garment 28 at the waist portion of the garment. The straps 29 in this embodiment of the invention support the leg portions of the garment and prevent the garment 28 from stretching to its extreme limit between the points where the upper and lower ends of the straps are secured to the garment.

In Fig. 7, one more embodiment of the invention is illustrated. Part of the front leg portion of an underwear garment is designated by the numeral 30 and a strap of less stretchable fabric than the fabric of the garment is designated by the numeral 31. The strap 31 is continuously sewed to the garment 30 from a point adjacent and preferably below the crotch of the garment to a point adjacent the waistline of the garment.

It will be seen that the form of the present invention can be considerably varied without departing from the scope of the invention. The various straps that are used may either be fixedly or detachably secured to the garment at one or both ends and, if desired, adjustment may be permitted at one or both ends of the straps. The straps can also be supported at their upper ends adjacent the waistline of the wearer in different manners. In whatever way that the straps are secured or supported, the straps will be stretchable to a shorter length between their attached portions than the length that the garment may attain when stretched to its full limit between the crotch and the waistline portion of the garment. It will thus be apparent that the stretching strain that would otherwise be exerted directly on the portion of the garment between the crotch and the waistline, while the garment is being worn, will be exerted against the straps. The straps will thus support the leg portions of the garment and will protect the portion of the underwear between the crotch and the waistline to prevent the same from ripping or tearing or binding on the body of the wearer.

It will, of course, be understood that various modifications and changes may be made in the form, details, arrangement and proportions of the various parts without departing from the scope of the present invention. It will be further understood that the device can be used with short underwear drawers as well as with long underwear drawers.

What is claimed is:

1. In a pair of underwear drawers, a device to support the leg portions of the drawers to prevent pulling and binding of the

drawers about the crotch, comprising a pair of fabric straps secured at their lower ends to the front leg portions of the drawers intermediate a vertical line taken through the crotch and the outer side edges of the drawers and adjustable securing means carried by said straps adjacent their upper ends to permit attachment of the upper ends of the straps to a garment worn about the waist of the wearer.

10 2. In a pair of underwear drawers, a device to support the leg portions of the drawers to prevent pulling and binding of the drawers about the crotch, comprising a pair of fabric straps secured at their lower ends to the front leg portions of the drawers intermediate a vertical line taken through the crotch and the outer side edges of the drawers, and loops at the upper ends of the said straps to permit attachment thereof to a trouser support.

15 3. The combination with underwear drawers, of a pair of fabric straps secured at their lower ends to the front leg portions of the drawers intermediate a vertical line taken through the crotch and the outer side edges of the drawers and adapted to be secured at their upper ends to a garment adapted to be worn about the waistline of the wearer, said straps being less stretchable between the 20 points of the attachment of the lower ends thereof and the waistline of the wearer than the drawers are stretchable between the points of attachment of the lower ends of 25 said straps and the waistline of the drawers.

30 4. In a pair of underwear drawers, a device to support the leg portions of the drawers to prevent pulling and binding of the drawers about the crotch, comprising a pair 35 of fabric straps secured at their lower ends to the front sides of the leg portions of the drawers intermediate a vertical line taken through the crotch and the outer side edges of the drawers, and the said straps having 40 a plurality of spaced loops formed at their upper ends to permit adjustable attachment 45 thereof to a trouser support.

50 5. In a pair of underwear drawers, a device to support the leg portions of the drawers to prevent pulling and binding of the drawers about the crotch, comprising fabric straps applied at their lower ends to the front leg portions of the drawers above the knees intermediate a vertical line taken 55 through the crotch and the outer side edges of the drawers, and means at the upper ends of said straps to permit attachment of the same to clothing of the wearer worn about the waist.

60 In testimony whereof I affix my signature.
HENRY C. DAUPHINAIS.
